(57) **CLAIM**

The ornamental design for a strap, as shown and described.

DESCRIPTION

FIG. 1 is a perspective view of a strap according to the present invention;

FIG. 2 is a front view of the strap of FIG. 1;

FIG. 3 is a rear view of the strap of FIG. 1;

FIG. 4 is a top view of the strap of FIG. 1;

FIG. 5 is a bottom view of the strap of FIG. 1;

FIG. 6 is a left side view of the strap of FIG. 1;

FIG. 7 is a right side view of the strap of FIG. 1; and,

FIG. 8 is a front perspective view of the strap of FIG. 1.

The broken lines in the figures merely illustrate the environment for the strap of the present design and therefore form no part of the claimed design.

1 Claim, 5 Drawing Sheets
